ARCHIE F. PARTCH, OF LOS ANGELES, CALIFORNIA.

APPARATUS FOR APPLYING PASTE TO BOX ENDS.

1,276,954.

Specification of Letters Patent. Patented Aug. 27, 1918.

Application filed January 21, 1918. Serial No. 212,928.

To all whom it may concern:

Be it known that I, ARCHIE F. PARTCH, a citizen of the United States, residing at Los Angeles, in the county of Los Angeles 5 and State of California, have invented certain new and useful Improvements in Apparatus for Applying Paste to Box Ends, of which the following is a specification.

The present invention relates to a paste 10 applying apparatus and more particularly to a type of apparatus designed for applying paste to the ends of boxes so that the same may be placed in a condition for application of a label to the pasted surface 15 thereof.

The invention has for its principal objects to provide a construction having a novel form of paste reservoir; one wherein the paste applied to the surface of the end 20 is removed from a point adjacent the side edges thereof, and one wherein the pasted ends are automatically stacked in a novel manner.

With the above mentioned and other objects in view, the invention consists in the novel construction and combination of parts hereinafter described, illustrated in the accompanying drawings and pointed out in the claims hereto appended; it being understood 25 that various changes in the form, proportion, size and minor details of construction within the scope of the claims may be resorted to without departing from the spirit or sacrificing any of the advantages 30 of the invention.

To more fully comprehend the invention, reference is directed to the accompanying drawings, wherein—

Figure 1 is a view in side elevation, partly 40 in section, of the preferred embodiment of my improved apparatus.

Fig. 2 is a view in top plan.

Fig. 3 is a cross sectional view taken on line 3—3 of Fig. 1, viewed in the direction 45 of the arrows.

Referring more particularly to the several views of the drawings, wherein like characters of reference designate corresponding parts, 1 indicates the uprights of a suitable 50 supporting frame carrying longitudinally disposed parallel spaced angle rails or tracks

2 which extend longitudinally the full length thereof, said tracks providing a horizontal conveyer. The box ends to be pasted are positioned in a suitable magazine 3 open 55 at its lower end above the conveyer 2 at one end of the same, and the lower edge of the front wall 4 of said frame terminates at a point immediately above the rails 2, the distance between the lower edge of said wall 4 60 and the horizontal portion of the respective rails being slightly greater than the thickness of a box end, permitting but one box end to be removed from the magazine at a time.

Extending upwardly from the wall 4 are the paste receptacle side walls 5 converging at their outer ends, as at 6, and said walls are connected at their lower edge by a curved bottom wall 7, overlying the conveyer rails and terminating short of the front ends of said side walls 5.

Paste is supplied to the receptacle through a connection 8 leading from a centrifugal pump 9, the feed opening of which connects 75 through a pipe 10 with the paste receptacle adjacent the lowest point thereof. It will be apparent that on the operation of the pump 9 the excess paste will be withdrawn from the paste receptacle, passed through 80 the pump and resupplied thereto.

Extending transversely over the conveyer rails 2 and above the same is a rotatable shaft 11 mounted in bearings 12, and carrying a suitable cylindrical brush 13 which is 85 of a length to lie intermediate the converging ends 6 of the walls 5 in contact therewith and is of a diameter to contact with the forward edge of the bottom wall 7 and thus provide a closure for the front wall of 90 the paste receptacle. In contact with said brush is an idler or paste removing roller 14 preferably positioned above the receptacle, the same being rotatably mounted in bearings 15 and lies in contact with the bristles 95 of the brush 13.

Pivotedly mounted, as at 15', to swing on a vertical axis with their rear ends positioned one in rear of the free outer ends of one of the walls 5 are the scraping members 16 which extend horizontally in parallel relation over the rails 2 of the conveyer.

Cooperating with the outer ends of the respective scrapers 16 are the leaf springs 17, which force the free ends of said scrapers into tight frictional contact with the pasted 5 ends as passed below the same. The springs connect with adjustable tension members 18 carried by a transversely disposed frame 19 arranged above the tracks 2 forming the conveyer, and carried by the side walls 10 thereof. The members 18 are mounted in guide slots 20 which permit of swinging movement of the outer ends of the scraper members toward each other to adjust the same to confine the paste to any given area 15 across the box ends.

The ends to be pasted are intermittently removed, lowermost one first, from the magazine, by a suitable feed member 21 slidably mounted in guides 22 disposed below the 20 tracks 2 and extending parallel therewith at a point beneath the lower end of the magazine. The feed member 21 carries at its rear end an upwardly spring pressed latch or 25 engaging pawl 23 having a beveled end 24 and pivotally mounted at its opposite ends, as at 25, to the feed member.

On successive reciprocation of said feed member 21 longitudinally of the guides 22, the vertical face 26 of the latch 23 will engage the rear edge of the lowermost box end 27 within the magazine and remove the same therefrom, forcing it longitudinally of the conveyer into the path of the brush 13. The ends 27 as successively removed from the 35 magazine contact at their forward edge with the rear edge of the end previously removed from said magazine, thus adjacent edges of the successively remaining ends are in meeting relation and the successive removal of 40 ends from the magazine causes movement of said removed ends longitudinally of the conveyer.

The mechanism for reciprocating the feed member 21 consists of a lever 28 fulcrumed 45 as at 29 at its lower end, and provided with a slot 30 at its upper end in which is received a pin 31 carried by a bracket 32 on the underside of the feed member.

The lever 28 carries within its length a 50 tubular guide or sleeve 33 fulcrumed to the lever, as at 34, and extending through said guide or sleeve is an operating rod 35 carrying the spaced collars 36 and 37 positioned one at each side of the sleeve 33, permitting 55 free movement of the rod relative to the lever. The opposite end of the rod 35 is pivotally connected, as at 38, to an arm 39 carried by a rotatable shaft 40 supported in bearings 41.

60 The shaft carries on its end a band wheel 42 around which extends a driving belt 43 driven from a suitable band wheel 44 on a shaft 45 rotatably supported in bearings 46 carried by the central support 1.

The shaft 45 is provided with a band 65 wheel 47 and is adapted to be driven in the direction of the arrow by power applied thereto from any suitable source. The shaft 45 also carries band wheels 48 and 49 which connect respectively with the pump 9 and 70 the brush 13 through the respective belts 50 and 51.

The pasted ends with the labels applied thereto after having traveled the full length of the runway, are lifted vertically from 75 the tracks 2 and are stacked within a suitable receiving chamber 52 formed by the vertical corner members 53 extending upwardly from the opposite ends of the tracks from the magazine by the following mechanism.

The rails 2 of the runway extend beneath the lower end of the chamber 52 and a lifting platform or plunger 54 is positioned between the same below said chamber and is 85 of an area approximately equal to the cross sectional area thereof. The platform 54 carries a supporting standard 55 which reciprocates through a guide 56, and said standard carries at its lower end a forked 90 guide 57 straddling the shaft 40, the guides 56 and 57 directing the vertical movement of the platform 54. An idler 58 is carried by the side wall of said guide 57 and the same rides on the peripheral surface of a 95 cam 59 carried by the shaft 40, the apex of said cam being disposed in a plane approximately 90 degrees from the arm 39. The labeled ends are lifted upwardly by the vertical upward movement of said platform 54 100 and stacked within said chamber 52 pass upwardly between the retaining dogs or pawls 60, pivotally mounted to swing on a horizontal axis, which on the downward movement of the platform contact with the 105 upper edge of the rails 2 and engage beneath the lowermost labeled end within the chamber and retain the end therein at a point above the tracks 2, permitting the free movement of a succeeding end beneath the same 110 for stacking.

The operation of my device may be briefly described as follows:—

The ends to be pasted and labeled are deposited in horizontal position in the magazine; paste is supplied to the reservoir 5 and power is supplied to the band wheel 47 to operate the same in the direction of the arrow Fig. 1.

The operation of the shaft 45 transmits 120 power to the shaft 40, causing movement of the arm 39, which during the first half revolution thereof from the position in Fig. 1, moves the rod 35 through spring 35' drawing said lever 28 forwardly, causing the 125 latch or pawl 23 to engage the lowermost end 27 in the magazine and slide the same therefrom longitudinally of the tracks 2

forming the runway to a point to pass beneath the brush 13, at which time paste is supplied to the upper surface thereof, as the brush is continually rotating. As successive 5 ends are removed from the magazine and conveyed toward the chamber, the successive removal of the lowermost end from the magazine causes a longitudinal movement of said removed ends beneath the paste applying roller 13, under the scrapers 16, and over the label applying station A to a point beneath the chamber 52. At the station A an operator stands who manually applies the desired labels to the pasted surface of 10 the ends as successively propelled past the station and toward the chamber 52. On the next one half revolution of the shaft 40, the cam 59 starts in its upward movement raising the platform 54 to lift the end thereover 15 upwardly within the chamber 52, over the dogs 60, and then to permit the lowering of the platform to a position as in Fig. 1. Along this path the rod 35 is moved longitudinally to slide the feed member rearwardly to operative position, as in Fig. 1 20 of the drawings.

If desirable, a tray 61 may be positioned beneath the paste applying roll 13 to retain any excess paste applied to the ends and removed therefrom by the scrapers 16.

In my improved construction I eliminate the endless conveyers commonly employed and convey the ends longitudinally of the runway by forcing the same in contact with 35 each other by an intermittent movement. I also provide a paste receptacle wherein the paste applying brush forms one wall thereof, thus insuring a uniform and ample supply of paste to each end and by my improved 40 stacking means am enabled to remove the labeled ends from the runway and place the same in stack formation without ruffling the freshly pasted labels on the surface thereof.

Having thus described my invention, what 45 I claim as new and desire to protect by Letters Patent is:—

1. An apparatus for applying paste to box ends for the applying of labels thereto, comprising a frame, a horizontally disposed 50 runway supported thereon, a magazine at one end thereof for containing a stack of ends to be pasted and labeled, a receiving chamber at the opposite end thereof for receiving the finished pasted and labeled ends, 55 means intermediate said magazine and receiving chamber for applying paste to the ends as conveyed from the magazine to the receiving chamber, said runway provided with a label applying station intermediate 60 said receiving chamber and said paste applying member, and reciprocating means for successively removing the lowermost end from the magazine and for forcing the removed ends longitudinally of said runway

with their edges in engagement into contact 65 with the paste applying means and thence into said receiving chamber.

2. An apparatus for applying paste to box ends for the applying of labels thereto, comprising a frame, a horizontally disposed 70 runway supported thereon, a magazine at one end thereof for containing a stack of ends to be pasted and labeled, a receiving chamber at the opposite end thereof for receiving the finished pasted and labeled ends, 75 means intermediate said magazine and receiving chamber for applying paste to the ends as conveyed from the magazine to the receiving chamber, said runway provided with a label applying station intermediate 80 said receiving chamber and said paste applying member, reciprocating means for successively removing the lowermost end from the magazine and for conveying the same longitudinally of the runway with their 85 edges in engagement into contact with the paste applying means and thence into said receiving chamber, and a vertically movable means cooperating with said receiving chamber for successively lifting the ends moved 90 thereinto upwardly into said chamber in stack formation, and means for retaining the stack in elevated position within said chamber on the withdrawal of said vertically movable means therefrom.

3. An apparatus for applying paste to box ends for the applying of labels thereto, comprising a horizontally disposed runway along which the ends to be pasted are conveyed, a paste receptacle positioned above 100 said runway and opened at one side across said runway, said receptacle provided with a bottom over said runway, a rotating paste applying member providing a closure for the open wall of said receptacle and for removing paste therefrom and applying the same to the box ends as passed beneath the same, means for conveying the ends longitudinally of said runway, and means for rotating said paste applying member.

4. An apparatus for applying paste to box ends for the applying of labels thereto, comprising a horizontally disposed runway along which the ends to be pasted are conveyed, a paste receptacle positioned above 115 said runway and opened at one side across said runway, a rotating paste applying member providing a closure for the open wall of said receptacle and for removing paste therefrom and applying the same to the box 120 ends as passed beneath the same, means in frictional contact with said brush in the direction of the rotation of the same after leaving said paste receptacle for removing the excess paste therefrom and depositing 125 the same within said receptacle.

5. An apparatus for applying paste to box ends for the applying of labels thereto,

comprising a horizontally disposed runway along which the box ends to be pasted are conveyed, means for applying paste to the ends as conveyed along said runway, means at each side of the runway and adjustable angularly transversely thereof for contacting with a portion of the pasted area of the box ends as conveyed for removing the paste therefrom and a spring coöperating with

each means for frictionally retaining said 10 means in contact with the pasted ends as successively conveyed under the same.

In testimony whereof I have signed my name to this specification in the presence of a subscribing witness.
